MESSAGE BOOK

Andrew J. Kennedy, Sr., Nashville, Tenn., assignor to The Egry Register Company, Dayton, Ohio, a corporation of Ohio

Application March 2, 1942, Serial No. 432,945

3 Claims. (Cl. 282—24)

This invention relates to a book containing a plurality of forms arranged in sets for producing a plurality of copies upon a single writing of the information upon one of the forms.

An object of the invention is to provide a book of forms wherein a plurality of copies of the forms is arranged in sets and is disposed within the book in a manner that one of the forms will be retained in the book while the remaining plurality of copies of a set of forms can be removed.

Another object of the invention is to provide a book of forms in accordance with the foregoing object wherein the cover for the book extends longitudinally around the same and provides a fly-leaf which can be positioned beneath a set of forms when being written upon.

It is another object of the invention to provide a book of forms arranged in sets having a plurality of copies arranged with interleaved carbon sheets in a manner that one of the forms can be retained in the book while the remaining copies of a set and the carbon sheets therefor can be removed from the book.

It is another object of the invention to provide a book of forms in accordance with the foregoing object wherein the copies of the forms removed from the book can be separated from the carbon sheets for suitable dispatch.

Another object of the invention is to provide a book of forms having a plurality of sets of different types of forms which can be used for different purposes.

Another object of the invention is to provide a pad of "all set" forms wherein one of the forms of each set is longer than the remaining forms thereof to permit a plurality of the "all set" forms to be secured together, the longer form providing a record copy.

Further objects and advantages of this invention will become apparent from the drawing and the following description.

In the drawing:

Figure 1 is a perspective elevational view of a book of forms shown in the closed position constructed in accordance with the teachings of this invention.

Figure 2 is a perspective elevational view of the book of forms shown in Figure 1 but with the cover portions thereof open to show the different types of forms contained within the book.

Figure 3 is an elevational view of one of the sets of forms contained in the book showing the manner in which certain of the copies are removed from the book.

Figure 4 is a perspective elevational view of a

set of forms that have been removed from the book showing the manner in which the interleaved carbon sheets are separated from the forms.

5 Figure 5 is a cross-sectional view of a set of forms, taken along line 5—5 of Figure 3, showing the manner in which the forms and interleaved carbon sheets are secured together.

10 Figure 6 is a cross-sectional view of the bound end of the book shown in Figure 1 and is taken along line 6—6 of Figure 1.

Figure 7 is a cross-sectional view of a modified arrangement of a set of forms showing the carbon disposed directly upon the back of the forms.

15 In this invention the book of forms consists of a plurality of individual sets of forms, each set containing a plurality of sheets. One of the sheets of the individual sets of forms is longer than the remaining sheets of the set so that a plurality of the sets of forms can be secured together in book form. The long sheets are adapted to be retained within a book formed by securing a plurality of sets together to form record copies which are permanently secured in book form.

20 The remaining sheets of the forms of each set are adapted to be separated from the record copy and thus removed from the book. Suitable carbon sheets are interleaved between the plurality of sheets of each set of forms so that a single writing upon the top sheet of each set will produce a plurality of copies. The carbon sheets are attached to the sheets of each set which is to be removed from the record copy of the set, whereby the carbon sheets are removed from the book each time the used set of forms is separated from the record copy.

25 After the used set of sheets is removed from the book of forms the carbon sheets can be separated from the forms to permit suitable dispatch of the forms. The carbon sheets may then be discarded or destroyed.

30 The sets of forms contained within the book may be similar sets or different types of forms, each arranged in suitable sets placed within a single book so that one book of forms will contain a plurality of different types of sets for recording various information, or for dispatching the sets of forms in different ways.

35 In the book of forms disclosed in this invention the book is divided into 3 sections, each section having a form of a different type. The major section 10 (see Figure 2) is composed of what may be called regular forms, that is, the sets of forms of this type consist of relatively

heavy sheets of paper having carbon sheets disposed between the paper sheets. A second section of forms 11 is provided beneath the major section 10 and may be referred to as thin forms, that is, the sheets which compose the sets of forms in section 11 are thin tissue sheets which have carbon sheets interleaved between the tissue sheets. These forms may be used for dispatching the information thereupon in a different manner than those forms which are removed from the major section 10. Either the same information can be placed upon the forms in section 11 as placed upon the forms in section 10, or the information may be of a different type.

A third section of forms 12 is disposed below the section 11. The section 12 may be adapted to receive different information than that placed upon either section 10 or 11, and in fact can be plain sheets of paper for copying directions to be forwarded with the information placed upon one of the forms in sections 10 or 11.

The book of forms 15 is provided with a cover 16 which extends longitudinally around the book in a continuous length. The cover 16 consists of a rear wall 18 which is formed around one end of a plurality of sets of forms which include sections 10, 11 and 12 to provide an end wall 19 and a top wall 20. The top wall 20 is provided with a fold line 21 so that the free end of the top wall 20 forms a front cover flap 17. Wire staples 22 extend through the top wall 20, the sections 10, 11 and 12 and the rear wall 18 to bind the sets of forms into book form.

The opposite end of the rear wall 18 is folded around the free end of the sets of forms to form an end wall 23 and a protecting writing flap 24 which is adapted to be disposed beneath a set of forms when writing is to be placed upon the set. When the book is closed, (as shown in Figure 1) the writing flap 24 can be disposed adjacent the front flap 17. A cloth reenforcing strip 25 is provided around the end wall 23 to reinforce this wall since the writing flap 24 is hinged upon the rear wall 15 each time a set of forms is to be used.

Each set of forms 40 consists of a plurality of record sheets having carbon sheets disposed therebetween. The carbon sheets are secured to the record sheet through which an impression is to be made and the record sheets are attached to each other to produce an all set form.

As shown in Figure 5, the record sheets 26, 27 and 28 are secured together by means of lines of adhesive 29. The carbon sheets 30 and 31 are disposed between the record sheets 26, 27 and 28 so that the carbon sheet 30 is secured to the record sheet 27 and the carbon sheet 31 is secured to the record sheet 28. The record sheet 28 is a top sheet upon which the original writing is placed so that it can be transferred through the carbon sheets to the record sheets 27 and 26 respectively.

The record sheets 26, 27 and 28 are provided with perforations 32, 33 and 34 extending transversely across the respective record sheets whereby the end portions of the record sheets and the carbon sheets can be removed from the main body of the record sheets.

The record sheet 26 is longer than the record sheets 27 and 28 and is the bottom sheet of the set of record sheets. The extending end 35 of the record sheet 26 is secured within the book 15 by means of the staples 22 which extend there-

through when the set of record sheets is disposed within the cover 16.

A plurality of sets of forms 40 is disposed within the book 15 in a manner that each record sheet 26 is secured within the binding end of the book 15 by means of the extending end 35. It can readily be seen that if a plurality of sets of forms 40 is disposed in adjacent relationship to form a book that the plurality of sheets in the main body of the set will produce a pack which is considerably thicker than the pack of sheets formed by the ends 35 of the individual record sheets 26. If the ends 35 of the record sheets 26 were bound in adjacent relationship, the binding end of the book would be considerably thinner than the main body of the book.

To avoid this difficulty spacer members 36 are disposed between the ends 35 of the record sheets 26 (as shown in Figure 6). As shown in this figure, 3 or 4 sets of forms 40 are disposed in adjacent relationship with the ends 35 extending therefrom in adjacent relationship. The ends 35 of the plurality of sets 40 are then placed between the spacers 36 so that a plurality of permanent record sheets 26 is retained between adjacent spacers 36. The binding end of the book 15 is thus made as thick as the main body of the book so that the cover flap 17 will lie flat upon the book when it is full.

The section 10 of the book 15 consists of a plurality of sets of forms 40 constructed in the manner shown in Figure 5. The section 11 of the book may be constructed in the same manner as the sets 40, but as previously described the record sheets 26, 27 and 28 of the section 11 are preferably of thin tissue. The section 12 can also be constructed in the same manner as the set 40 but, as disclosed in this invention, the section 12 is preferably individual sheets of thin copy or tracing paper.

The sections 10, 11 and 12 are placed in their proper relationship with the perforated ends of the sections 10 and 11 positioned at the free end of the book 15 and the extending ends 35 of the sheets 26 disposed within the binding end of the book. A stiffener sheet 37 is disposed beneath the section 12 and is preferably a material having sufficient stiffness to permit the book 15 to be held in the hand of an individual while writing upon one of the form sets 40, thus eliminating the necessity of any special writing support.

To assemble the book of forms of this invention the sections 12, 11 and 10 are placed upon the stiffening sheet 37 in the order mentioned and the spacing members 36 are placed between every third or fourth sheet 26 of the sets 40. The cover 16 is then formed around the end of the assembly thus provided and the wire staples 22 are driven therethrough.

When using the book of forms the writing flap 24 is positioned beneath one of the sets 40 to prevent transferring the information to the sheets below the pad of sheets being used. After the information has been transferred to the set of forms 40 the upper right hand corner of the forms is grasped by the fingers and forced outwardly and downwardly to tear the record sheet 26 along the perforated line 32 (as shown in Figure 3). This operation removes the record sheets 27 and 28 and the carbon sheets 30 and 31 from the book 15 and leaves the record sheet 26 in the book. The record sheet 26 is of course retained in the book since the extending end 35 is fastened within the binding end of the book 15.

After the record sheets 27 and 28 and the car-

bon sheets 30 and 31 have been removed from the book 15, the record sheets can be separated from the carbon sheets by grasping one end of the record sheets at the corner thereof and the opposite end between the perforation line 34 and the end of the sheet to tear the body of the record sheets 27 and 28 from the ends thereof. Since the carbon sheets 30 and 31 are secured to the record sheets 27 and 28 respectively between the perforation lines 33 and 34 and the end of the record sheets, the carbon sheets 30 and 31 will be separated from the body of the record sheets 27 and 28 by this operation (as shown in Figure 4). The carbon sheets can then be destroyed. The carbon sheets 30 and 31 are somewhat shorter than the record sheets 27 and 28 to permit this last operation to be performed (as shown in Figure 5).

It is of course to be understood that if one of the sets of record forms in the section 11 of the book is to be used, that the same procedure as just described can be followed. Also, it is to be understood that the thin tracing sheets in the section 12 of the book can be torn from within the book along suitable perforation lines provided adjacent the bound end of the book.

The book of forms described herein is particularly adapted for field use by the armed forces wherein the regular forms in section 10 of the book can be used for normal dispatch, the thin tissue forms in section 11 of the book are suitable for dispatch by carrier pigeon, while the tracing sheets in section 12 of the book are adapted for reproducing maps and drawings for dispatch with the message. The carbon sheets used between the forms are preferably of a special variety which is weather resistant and will not become brittle when subjected to low temperatures and will not smudge when subjected to high temperatures.

In Figure 7 there is shown a modified form of the set of sheets 40a wherein a film of carbon 38 and 39 is applied upon the sheets 28a and 27a. The bottom sheet 26a is not provided with a carbon film. The use of the arrangement shown in Figure 7 avoids the necessity of using separate carbon sheets as heretofore described and may have particular military value since the destruction of the carbon sheets no longer becomes a problem.

While the form of the invention described herein is a preferred form of the invention, yet it is to be understood that the instrument of this invention is subject to modification without departing from the spirit of the invention, and that such modifications as fall within the scope of the appended claims are intended to be included herein.

Having thus fully described my invention what I claim as new and desire to secure by Letters Patent is:

1. A book adapted for use in producing a plurality of copies of an original instrument which consists of, a stiff backing member, a plurality of sets of sheets positioned upon said backing member, each set of sheets consisting of; a plurality of individual copy sheets with transfer sheets interleaved therebetween, at least one of the copy sheets of each of said sets being substantially longer than the remaining sheets, adhesive means securing the ends of each copy sheet together opposite to the extending end of said long sheet, adhesive means securing the transfer sheets to the copy sheets adjacent the adhesive means for securing the copy sheets together, lines of perfora-

tion in said copy sheets adjacent the lines of adhesive securing the transfer sheets to said copy sheets, said transfer sheets being shorter than said copy sheets at the end thereof opposite to the end whereby the transfer sheets are secured to the copy sheets; a plurality of said long sheets being disposed between thick spacer members to build up thickness at the extending end of said long sheets equal to the body of the stack of plurality of sets of sheets, a cover member for said sets of sheets consisting of; a back portion disposed against said backing member, an end fly-leaf extending from said back portion to fold over the adhesively secured ends of said sets of sheets to cause said fly-leaf to lay upon the uppermost sheet of said sets, a second fly-leaf portion extending from the opposite end of said back portion and folded over the extending ends of said long sheets of said sets and said spacer members to cause said second fly-leaf portion to lay upon said first fly-leaf portion; and fastening means extending through said last mentioned end of said book to secure said sets of sheets between said last mentioned fly-leaf portion and said backing member and said backing member to said back portion of said cover member.

2. A book adapted for use in producing a plurality of copies of an original instrument which consists of, a stiff backing member, a plurality of sets of sheets positioned upon said backing member, each set of sheets consisting of; a plurality of individual copy sheets with transfer sheets interleaved therebetween, at least one of the copy sheets of each of said sets being substantially longer than the remaining sheets, adhesive means securing the ends of each copy sheet together opposite to the extending end of said long sheet, adhesive means securing the transfer sheets to the copy sheets adjacent the adhesive means for securing the copy sheets together, lines of perforation in said copy sheets adjacent the lines of adhesive securing the transfer sheets to said copy sheets, said transfer sheets being shorter than said copy sheets at the end thereof opposite to the end whereby the transfer sheets are secured to the copy sheets; a plurality of said long sheets being disposed between thick spacer members to build up thickness at the extending end of said long sheets equal to the body of the stack of plurality of sets of sheets, a cover member for said sets of sheets consisting of; a back portion disposed against said backing member, an end fly-leaf extending from said back portion to fold over the adhesively secured ends of said sets of sheets to cause said fly-leaf to lay upon the uppermost sheet of said sets, a cloth reinforcing strip extending transversely of said cover member between said back portion and said fly-leaf portion, a second fly-leaf portion extending from the opposite end of said back portion and folded over the extending ends of said long sheets of said sets and said spacer members to cause said second fly-leaf portion to lay upon said first fly-leaf portion; and wire stitching means extending through said last mentioned end of said book to secure said sets of sheets between said last mentioned fly-leaf portion and said backing member and said backing member to said back portion of said cover member.

3. A book adapted for use in producing a plurality of copies of an original instrument which consists of, a stiff backing member, a plurality of sets of sheets positioned upon said backing member, each set of sheets consisting of; a plurality of individual copy sheets with transfer sheets in-

terleaved therebetween, at least one of the copy sheets of each of said sets being substantially longer than the remaining sheets, adhesive means securing the ends of each copy sheet together opposite to the extending end of said long sheet, adhesive means securing the transfer sheets to the copy sheets adjacent the adhesive means for securing the copy sheets together, lines of perforation in said copy sheets adjacent the lines of adhesive securing the transfer sheets to said copy sheets, said transfer sheets being shorter than said copy sheets at the end thereof opposite to the end whereby the transfer sheets are secured to the copy sheets; a plurality of said long sheets being disposed between thick spacer members to build up thickness at the extending end of said long sheets equal to the body of the stack of plurality of sets of sheets, a plurality of individual sheets disposed between said backing member and the lowermost sheet of said sets of

20 sheets and having lines of perforation adjacent the spacing members to permit separation of said individual sheets from the book, a cover member for said sets of sheets consisting of; a back portion disposed against said backing member, an end fly-leaf extending from said back portion to fold over the adhesively secured ends of said sets of sheets to cause said fly-leaf to lay upon the uppermost sheet of said sets, a second fly-leaf portion extending from the opposite end of said back portion and folded over the extending ends of said long sheets of said sets and said spacer members to cause said second fly-leaf portion to lay upon said first fly-leaf portion; and fastening means extending through said last mentioned end of said book to secure said sets of sheets between said last mentioned fly-leaf portion and said backing member and said back portion of said cover member.

ANDREW J. KENNEDY, SR.
